UNITED STATES PATENT OFFICE

170,450

COMBINATION AIR PURIFIER AND TELEPHONE SET BASE

David C. Craig, Los Angeles, Calif.

Application June 11, 1953, Serial No. 25,435

Term of patent 3½ years

(Cl. D26—14)

To all whom it may concern:

Be it known the I, David C. Craig, a citizen of the United States, residing in the city of Los Angeles, in the county of Los Angeles and State of California, have invented a new, original, and ornamental Design for a Combination Air Purifier and Telephone Set Base, of which the following is a specification, reference being had to the accompanying drawing, forming part thereof.

Fig. 1 is a perspective view looking toward the front of a combination air purifier and telephone set base, showing my new design.

Fig. 2 is a side elevation thereof.

Fig. 3 is a rear elevation thereof, with a por-

tion of the right side broken away for convenience of illustration.

The dominant features of my design reside in those portions shown in full lines.

I claim:

The ornamental design for a combination air purifier and telephone set base, substantially as shown and described.

DAVID C. CRAIG.
